UNITED STATES PATENT OFFICE.

JOHN E. BUCKLIN, OF WASHINGTON, DISTRICT OF COLUMBIA.

TOBACCO DRESSING AND FEEDING MACHINE.

SPECIFICATION forming part of Letters Patent No. 531,259, dated December 18, 1894.

Application filed September 16, 1893. Serial No. 485,708. (No model.)

To all whom it may concern:

Be it known that I, JOHN E. BUCKLIN, a citizen of the United States, residing at Washington, in the District of Columbia, have invented certain new and useful Improvements in Tobacco Dressing and Feeding Machines; and I do hereby declare the following to be a full, clear, and exact description of the invention, such as will enable others skilled in the art to which it appertains to make and use the same.

My present invention relates to devices for automatically presenting tobacco to the cigarette forming devices of cigarette machines and consists in certain novel constructions and combinations of parts forming an improved tobacco dresser and feeder.

The best form in which I have contemplated embodying my invention is shown in the accompanying drawings and the invention is fully disclosed in the following description and claims.

Referring to the said drawings, Figure 1 is a right side view of my improved device. Fig. 2 is a left side view of the same. Fig. 3 is a central vertical section of the same. Fig. 4 is an enlarged vertical section of the central portion of the machine. Fig. 5 is an enlarged view of the tobacco receiving hopper and its adjunctive mechanism. Fig. 6 is a top plan view of the central portion of the machine. Fig. 7 is a vertical transverse section through the delivery passage of the machine. Fig. 8 is a top plan view of the tobacco receiving hopper and the tobacco separating devices located therein. Figs. 9 and 10 are enlarged vertical sectional views of the tobacco hopper showing the separating devices. Fig. 11 is a detail sectional view of said separating devices, and Fig. 12 is an enlarged view showing the parts of said devices in detail.

Much difficulty is experienced in the mechanical feeding of tobacco in cigarette and like machines as the tobacco is liable to be bunched and impacted together causing clogging of the feeding devices and imperfect and uneven feed and resulting in a loss by reason of imperfect articles of the class manufactured.

The object of my invention is to provide a machine for feeding tobacco that will have little or no liability to clog and which will be

able to feed the tobacco in a layer of substantially uniform volume. To do this I employ a series of three groups of devices, one of which I term the separating devices and which is first to act on the tobacco. The next I denominate the feeding devices, which receive the tobacco from the separating devices, and the third group I term the delivery devices and which condense the tobacco into a layer of the size and thickness desired and discharge the same from the machine.

The different groups of devices will be particularly described in the order in which they are here named.

A represents the frame work of the machine which is constructed so as to receive and support the various parts of the mechanism.

In the upper part of the casing is located a tobacco receiving hopper B in which are located the tobacco separating devices. In the bottom of the hopper B is a horizontal endless belt or conveyer b supported upon a pair of driving rollers b' b' mounted in the sides of said frame. Above this conveyer projecting from the back wall of the hopper downwardly is an inclined plate or chute B' which tends to force the tobacco deposited in the hopper toward the front of the same and into engagement with the separating devices.

In the front part of the hopper adjacent to the front end of the conveyer b is a picker C consisting in this instance of a roller provided with straight or curved spikes or teeth for separating the tobacco as it passes from the conveyer b. This picker is rotated in such a manner that its teeth pass in an upward direction when they engage the tobacco and carry it over and drop it in a loosened condition.

In order to insure the discharge of the tobacco and the clearing of the teeth of the picker I employ on the delivery side of the picker the clearing brush E which rotates in such a manner that the side of the brush which engages the picker travels in the same direction as the picker teeth but at a greater speed thereby brushing and cleaning all of the tobacco from the teeth and leaving it in a light and loosened condition.

In order to positively regulate the amount of tobacco taken by the teeth of the picker from the conveyer b I provide the comb D which is rigidly secured to a rock shaft d and

- is mounted in the sides of the hopper, and said comb is provided with teeth d' which lie between adjacent rows of the picker teeth. The rock shaft d is provided with an arm d^2 outside the hopper and said arm is provided with adjusting devices consisting in this instance of a link d^3 , see Fig. 1, pivoted to the arm d^2 and having a slot engaging a stationary pin on the side of the hopper which is provided with a screw threaded adjusting nut, d^4 . By this means the position of the comb D can be varied so as to allow the teeth of the picker to project a greater or less amount beyond said comb and take up a greater or less amount of tobacco, as will be readily understood. The comb D also assists the picker teeth in separating the tobacco and preventing the passage of bunches or masses of tobacco from the picker.
- In order to prevent the tobacco from becoming packed at the bottom of the hopper, as it otherwise would, I provide a stirrer B^2 for agitating the tobacco in the hopper and holding the bulk of it back from the separating devices, allowing only a comparatively small quantity to fall upon the conveyer b at a time, and I also provide a rake for positively feeding the tobacco on the forward end of the conveyer b up to the picker teeth. These devices are shown best in Figs. 5, 8, 9, 10, 11 and 12. The stirrer B^2 is of the form of a multi-tined fork and consists of a series of teeth on the lower end of a vertically disposed rod b^2 pivoted at its upper end to a horizontal link b^3 which is pivoted at b^4 to a stationary part connected with the hopper. The vertical rod b^3 connected to the fork stirrer is provided intermediate its ends with an eccentric strap b^5 which engages an eccentric b^6 on a cross shaft B^3 mounted in bearings at the upper part of the hopper and operated to impart a backward raking movement to the stirrer B^2 . The teeth of the stirrer are inclined forward slightly so as to engage the tobacco adjacent to the front end of the belt or conveyer b and draw it backward, allowing only a certain part of the tobacco to remain upon the conveyer and be carried to the picker.
- Forward of the stirrer B^2 is a pair of guides or ways f pivoted to the sides of the hopper at f' and adapted to receive and guide the vertically moving feeding rake F which is provided with a series of depending teeth, f^2 . See Figs. 5, 11 and 12.
- To the feeding rake F is secured a pair of arms f^3 which extend upward and are connected with eccentric straps f^4 engaging eccentrics f^5 on the cross shaft B^3 as shown.
- See particularly Figs. 5, 9 and 10. It will thus be seen that the eccentrics will impart to the rake F an upward and downward movement in the guides f and that the said guides will also oscillate upon their pivots f' thus imparting a forward feeding movement to the rake causing the points of its teeth to move in an ellipse, as will be readily understood,

and enabling the rake teeth to positively feed the tobacco up to the teeth of the picker C . I also provide means for regulating the action of the feeding rake F and to this end I provide a plate F' see Figs. 11 and 12, which engages the rear face of the rake F and is connected thereto by a pin f^6 engaging a slot f^7 in the plate F' , said pin having a head on the outside of said plate.

The lower end of the plate F' is provided with a forwardly extending flange f^8 which carries a series of tubular guides f^9 and the teeth f^2 of the rake F extends through said tubular guides f^9 and the flange f^8 as clearly shown in Fig. 11. The upper end of the plate F' is provided with an extension f^{10} having an aperture therein which is engaged by a rigid arm d^5 secured to the rock shaft d of the comb D and projecting rearwardly. It will thus be seen, by reference to Fig. 11, that when the rock shaft d is adjusted to vary the position of the comb D , the rigid arm d^5 will cause an upward or downward movement of the plate F' carrying the tubular guides f^9 and adjust said plate and guides with respect to the rake F , thus exposing a greater or less amount of the rake teeth f^2 . The tubular guides f^9 also assist in the clearing or stripping of the teeth f^2 of the rake.

The feeding devices of the machine are as follows: Below the picker C and clearing brush E is located an inclined board or chute e which guides the tobacco dropping upon it from the picker, to a pair of feeding and macerating rolls $G G$ which feed it forward to a beater H located just in advance of the feed rolls. The beater H consists of a roller provided on its periphery with a series of projections or teeth h which loosen up the tobacco still more and feed it downward along an inclined chute or slide h' supported from the sides of the machine frame. Adjacent to its lower end this chute or slide h' is slightly concave or trough shaped and above it is a pneumatic feeding cylinder or roller K which has its periphery provided at intervals alternately with transverse brushes k and transverse fan blades k' capable of producing a current of air, when the cylinder or roller is rapidly rotated, which assists the forward feeding movement of the tobacco which has been thoroughly loosened by the separating devices and the beater H .

I denominate the cylinder or roller K a "pneumatic feeding roller" as the tobacco passes between the roller and the bottom of the chute h' and is fed forward positively by direct contact with the roller. At the same time it creates a blast and assists the further forward movement of the tobacco after it has left the roller.

The beater H and the pneumatic feeding cylinder K are covered in by a portion A' of the frame or casing which I prefer to make removable so that the parts can be readily inspected when desired.

Immediately in front of the lower end of

the chute h' and forward of the pneumatic feeding cylinder I locate the condensing chamber L which is deeper at the rear end than at the forward end where it communicates with the delivery passage M of the machine. The condensing chamber has its top wall which is inclined to gradually lessen the depth of said chamber, provided with a series of fine apertures see Figs. 3 and 6 to allow the air forced into said chamber by the pneumatic feeding cylinder to escape and the tobacco is gradually condensed and compressed in this chamber into a stream or ribbon which passes out through the delivery passage M.

Beneath the condensing chamber L is a large pulley l, engaged by a conveyer belt m passing around said pulley through the lower part of the delivery passage M around a pulley m^2 at the front end of the same and rearward over suitable idle pulleys m^1 m^3 to the pulley l, one of said idle pulleys being preferably provided with a belt tightening device as indicated at m^2 provided with a weight to maintain the desired tension of the said belt. The belt m forms the bottom of the condensing chamber L for a greater portion of its length, the lower wall of said chamber being cut away as indicated at l' for this purpose. At each end of the delivery passage M above the same is a roller m^4 carrying a horizontal conveyer belt m^4 which passes along the upper part of the delivery passage M above and at a uniform distance from the lower belt m. It will thus be seen that the tobacco after it has been condensed in the condensing chamber L will be passed out through the delivery passage M by the upper and lower conveying belts m^4 m, the adjacent portions of which will be caused to travel in the same direction and at the same rate of speed. From the delivery passage M the tobacco will pass in a uniform compact sheet or ribbon to the cigarette forming devices of a cigarette machine and it will be observed that while the greater portion of the air forced into the condensing chamber will escape through the apertures in the top wall of said chamber, the influence of the current of air will be felt throughout the length of the delivery passage and will assist in the uniform delivery of the tobacco therefrom.

I prefer to provide the side walls of the delivery passage with glass plates M' as indicated in the drawings so that the thickness and compactness of the sheet or stream of tobacco passing through the same may be seen from the outside of the machine, thus enabling the operator to adjust the tobacco separating devices so that they will furnish a greater or less amount of tobacco to the feeding and delivery devices of the machine.

It is desirable to provide the upper feeding roll G with a tension device to hold it yieldingly in close proximity to the lower roll and for this purpose I prefer to employ the construction shown in the drawings. See Figs. 1 and 3. A pair of levers g g is pivoted to the

casing and engage the bearing to the upper feed roll. Springs g' are secured to the levers g g and to a stationary part of the frame in such a manner as to exert a constant pressure upon the upper roll and upon any tobacco passing between the rolls G G.

N represents the driving shaft of the machine provided with a driving pulley N' to which power may be applied in any desired way. From this driving shaft N power is transmitted to the various working parts of the device in such a manner as to give each the required movement in the desired direction. In the drawings I have illustrated the operative connections of the various parts with the driving shaft and I have indicated the direction of rotation of the various parts by arrows.

The operation of the device is as follows: The tobacco to be treated is deposited in the hopper B and falls upon the endless conveyer b located in the bottom thereof. The stirrer B² will constantly operate to draw back the tobacco from the forward end of the hopper and allow only a small portion of it to remain upon the belt by which it is carried forward into engagement with the feeding rake F which positively feeds it up to the picker C. The teeth of the picker C receive the tobacco from the conveyer b and carry it through the teeth of the comb D up and over the picker to the clearing brush E which brushes it from the teeth of the picker and deposits it in a loose and lightened condition upon the inclined chute e which conveys it to the feeding rolls G G. The group of devices which act upon the tobacco until it passes from the clearing brush E I term the tobacco separating devices. The tobacco next passes to the group of devices which I term the feeding devices. Passing through the feeding and macerating rolls G G it is delivered to the beater H which further loosens it and passes it down the inclined chute h' to the pneumatic feeding roll K by which it is delivered with a volume of air to the next group of devices which I term the delivery devices. From the pneumatic feeding roller K the tobacco is delivered to the condensing chamber L where it is gradually compressed and condensed by the expulsion of the air through the series of apertures in the upper walls of the chamber and by the tapering form of said condensing chamber and it is then carried by the conveyer belts m m^4 through the delivery passage M.

As before stated the tobacco separating devices can be adjusted in such a manner that the picker will take up a greater or less amount of tobacco in a given time and in this way the stream or ribbon of tobacco may be delivered in a more or less thick and compact condition.

What I claim, and desire to secure by Letters Patent, is—

1. The herein described tobacco dresser and feeder, comprising among its members a pneumatic feeding roller, substantially as described.

2. The herein described combination with devices for separating and lightening the tobacco of a pneumatic feeding roller, substantially as described.
- 5 3. The herein described tobacco separating devices comprising a movable rake, and a stirrer cooperating therewith to divide off a part of the tobacco and move it forward.
4. In a tobacco dresser, a hopper provided with tobacco feeding devices consisting of a movable rake for moving a portion of the tobacco toward the delivery side of the hopper and a fork stirrer cooperating therewith, substantially as described.
- 10 5. The combination with the pneumatic feeding roller, of the condensing chamber and the delivery passage, substantially as described.
6. The combination with the pneumatic feeding roller, of the delivery passage and condensing chamber one of the walls of the two latter devices being provided with an air outlet, substantially as described.
- 15 7. The combination with devices for separating and lightening the tobacco, of the pneumatic feeding roller, the delivery passage and condensing chamber, substantially as described.
8. A tobacco dresser provided with tobacco separating devices, a picker, a conveyer and a feeding rake movable upon and longitudinally of the conveyer, substantially as described.
- 20 9. In a tobacco dressing and feeding mechanism, the combination with a hopper, of an endless conveyer located at the bottom thereof, a feeding rake having a downward movement upon the conveyer, a forward movement upon said conveyer and then a backward and upward movement, and a stirrer cooperating with said rake to separate the tobacco in the hopper, and actuating devices substantially as described.
- 25 10. In a tobacco dressing and feeding device the combination with a hopper, of an endless conveyer in the bottom of the same and tobacco separating devices consisting of a rake moving toward the delivery side of the hopper and a stirrer moving in the opposite direction, and actuating devices substantially as described.
- 30 11. A tobacco dresser provided with tobacco separating devices consisting of the picker, the movable feeding rake for feeding the tobacco toward said picker and the stirrer for forcing portions of the tobacco away from said picker and the endless carrier for conveying tobacco from said stirrer to the picker, substantially as described.
- 35 12. In a tobacco dresser the combination with the pneumatic feeding roller, of the condensing chamber having tapering walls and an air outlet other than the discharge passage, substantially as described.
- 40 13. In a tobacco dresser the combination with the pneumatic feeding roller, of the condensing chamber provided with tapering walls, one of said walls being perforated to allow the escape of air, substantially as described.
- 45 14. In a tobacco dresser the combination with the pneumatic feeding roller, of the condensing chamber provided with tapering walls, a delivery passage communicating with said condensing chamber and a conveyer forming a portion of the walls of the condensing chamber and delivery passage, substantially as described.
- 50 15. In a tobacco dresser the combination with the picker, of the adjustable comb, and the conveyer, the feeding rake movable upon and longitudinally of said conveyer and adjusting devices for said rake, substantially as described.
- 55 16. In a tobacco dresser the combination with the picker, of the comb and the feeding rake, adjusting devices for said comb and adjusting mechanism for said rake connected with said comb adjusting mechanism, substantially as described.
- 60 17. In a tobacco dresser the combination with the hopper, of the conveyer, the pivoted guides, and the rake moving in said guides, and the adjustable plate provided with a stripper flange, substantially as described.
- 65 In testimony whereof I affix my signature in presence of two witnesses.
- 70 JOHN E. BUCKLIN.
